NO. 14,490

DEC 18, 1883

UNITED STATES PATENT OFFICE.

H. CLAY BASCOM AND CYRUS A. HODGES, OF TROY, N. Y., ASSIGNORS TO N. S. VEDDER PATTERN WORKS, BASCOM, GALBRAITH & CO., OF SAME PLACE.

DESIGN FOR A COOKING-STOVE.

SPECIFICATION forming part of Design No. 14,490, dated December 18, 1883.

Application filed November 3, 1883. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Cooking-Stoves, of which the following is a specification, reference being had to the accompanying cut, print, or engraving, representing our said design.

The design for the side of the stove consists of the oven-door A and fire-box door B, shaped, ornamented, and arranged upon the plate C so as to present the appearance represented in the said print.

The design for the front of the stove consists of the fire-door D and front plate, E, shaped, ornamented, and arranged so as to present the appearance represented in the aforesaid cut.

The design for the side plate, F, of the rear extension is composed of the panel G, reversely-curved lower part, a, and oblique ornament b, all shaped and arranged substantially as shown.

The design for the oven-door A consists of the central rhombic panel ornament, H, and the oblique ornamented band c, shaped and arranged together as shown, with or without the ornamentations d.

The design for the panel ornament H consists of the rhombic border e, inclosing the central rosette ornament, f, all shaped and arranged together as shown, with or without the ornaments g.

The design for the door or panel B or G consists of the rhombic panel ornament h and oblique ornamental band i, shaped and arranged together as shown, with or without the ornaments j.

The design for the front door, D, consists of the row of mica light-openings k, with the intervening ornaments, l, in connection with the series of draft-apertures m and intermediate oblique ornaments, n, all shaped and arranged together as shown.

The design for the front plate, E, consists of the two panels o, each having thereon the oblique band ornament p and the semicircular top and bottom ornaments, q, all shaped and arranged together as shown.

The design for the legs consists of the concavely-curved lower part, r, and convex upper portion, s, having the obliquely-arranged band t, and ornamented so as to present the appearance represented in the accompanying engraving.

We claim as our invention—

1. The design for the side of the stove, composed of the parts A B C, shaped and ornamented as set forth.

2. The design for the stove-front, composed of the parts D and E, shaped and ornamented as set forth.

3. The design for the rear extension plate, F, composed of the parts G a b, shaped and arranged as shown and described.

4. The design for the oven-door A, composed of the parts H and c, as shown and described.

5. The design for the panel ornament H, composed of the parts e f, shaped and arranged as set forth and shown.

6. The design for the door or panel B or G, composed of the parts h and i, shaped and arranged as set forth.

7. The design for the front door, D, composed of the parts k l and m n, as shown and described.

8. The design for the front plate, E, composed of the parts o p q, as shown and described.

9. The design for the legs, composed of the parts r s t, shaped and ornamented as set forth.

In testimony whereof we hereunto set our hands, in the presence of two subscribing witnesses, this 1st day of November, 1883.

H. CLAY BASCOM.
CYRUS A. HODGES.

Witnesses:

CHARLES H. BENEDICT,
CHESTER BASCOM.
